(57) **CLAIM**

The ornamental design for a tabletop cooling device, as shown and described.

DESCRIPTION

FIG. 1 is a perspective top view of my new design for a tabletop cooling device with foldable supporting legs, with the legs in an open position.

FIG. 2 is a perspective bottom view thereof, with the legs in an open position.

FIG. 3 is a side view thereof, with the legs in an open position.

FIG. 4 is a back view thereof, with the legs in an open position.

FIG. 5 is a bottom view thereof, with the legs in an open position.

FIG. 6 is a back view thereof, with the legs in a closed position.

FIG. 7 is a bottom perspective view thereof, with the legs in a closed position.

FIG. 8 is a top view thereof, with the legs in an open position.

FIG. 9 is a top perspective view thereof, with the legs in a closed position.

FIG. 10 is a bottom view thereof, with the legs in a closed position.

FIG. 11 is a front view thereof, with the legs in an open position.

FIG. 12 is a front view thereof, with the legs in a closed position.

FIG. 13 is a side view thereof, with the legs in an open position; and,

FIG. 14 is a top view thereof, with the legs in a closed position.

The broken lines shown in the drawings illustrate unclaimed portions and form no part of the claimed design.
